Attorney.

UNITED STATES PATENT OFFICE.

ALEXIS W. PEVARE, OF BOSTON, MASSACHUSETTS.

PHONOGRAPH.

1,292,368.

Specification of Letters Patent.

Patented Jan. 21, 1919.

Application filed November 30, 1917. Serial No. 204,590.

To all whom it may concern:

Be it known that I, ALEXIS W. PEVARE, a citizen of the United States, residing at Boston, in the county of Suffolk and State of Massachusetts, have invented certain new and useful Improvements in Phonographs, of which the following is a specification.

The object of my invention is to improve the quality of the sound reproduction obtainable from phonographs by providing such instruments with means whereby vibrations other than those intended to be reproduced by the needle, such as mechanical noises due to the operation of the motor and to the metallic character of various structural parts of the instrument, will be largely suppressed. The invention can be readily embodied in an attachment adapted to be applied to existing phonographs without structural alteration of the latter, and such an attachment as constructed for use in a phonograph of the usual disk-record type is hereinafter described in connection with the accompanying drawing, in which:—

25 Figure 1 is a face view of the under side of the horizontal board usually employed in phonographs for carrying the motor, with my attachment applied thereto, and

30 Fig. 2 is a transverse section on the line 2—2 Fig. 1, showing also in side elevation the rotating table which carries the record.

In the drawing, which shows only such parts of a phonograph as are required for explaining my invention, 2 indicates the board which carries the motor on its under side, 3 indicates the motor, of which only the frame is shown, 4 indicates the table which is rotated by the motor and carries the record, and 5 indicates the spindle by which the table 4 is supported and connected to the motor. The specific construction of these parts is immaterial to my invention, the construction illustrated being such as is commonly employed in a Victor phonograph, in which the board above referred to is supported on a pair of hinges represented in part by the clips shown at 6—6.

My attachment consists essentially of a sheet 7 made of soft rubber and provided with a soft-rubber rib 8 adapted to surround the motor, the rib being preferably integral with the sheet. The attachment is secured to the under side of the board 2 with the sheet 7 located between the board and the motor and with the rib 8 projecting downwardly and extending completely

around the motor at a short distance therefrom, as shown in Fig. 1. The sheet 7 is preferably about $\frac{3}{2}$ nds of an inch in thickness and has a margin outside of the rib for attachment purposes. It is also provided with a perforation 9 through which the spindle 5 passes, this perforation being preferably of the same size as the overlying hole in the board 2. While the size of the rib 8 and its distance from the motor frame may be varied somewhat, for a phonograph of medium size I prefer to employ a rib of about $\frac{5}{8}$ ths of an inch square in cross-section and to locate the rib about half or three-quarters of an inch from the motor frame, although it is not necessary for the rib to curve inward to this extent at points where the motor frame is laterally indented. In general, the smaller the rib the closer it should be located to the motor frame, but in any case it should have sufficient mass to absorb the vibrations which it is intended to eliminate. If the rib is too large, or if the sheet 7 is too thick, the tones produced by the phonograph will be deadened.

The attachment above described is preferably provided with a cover conforming in outline to the sheet 7 and consisting of a flat outer flange 10 adapted to rest on the margin of the sheet 7, an inner flange 11 shaped to surround the motor frame at a short distance therefrom and a vertical portion 12 which connects the two flanges and is of such dimensions that it and the inner flange are located close to but out of contact with the rib 8. The cover when employed is preferably made of hard rubber and is secured in place by screws 13 passing through the flange 11 and through the margin of the sheet 7 into the board 2. It is not essential, however, and is not shown in Fig. 1, its principal function being to protect the soft rubber parts and present an attractive appearance.

I have found that the addition of my attachment to a phonograph results in a marked improvement in the tone of the instrument, which is slightly increased in volume and made much clearer, so that certain parts of records can be heard which were not previously noticed. It also lessens the noise made by the needle and practically eliminates the metallic sound which is so perceptible in ordinary phonographic tones. It has a particularly noticeable effect on vocal records by accentuating the distinction

between the vocal tones and the accompaniment. These results are very largely due to the presence of the rib, as distinguished from the mere cushioning effect of the sheet which carries the rib, and apparently the rib acts by absorbing or otherwise suppressing vibrations originating in the motor itself or transmitted thereto from the rotating table without in any way affecting the reproduced vibrations transmitted by the needle to the horn, the latter vibrations being thus given forth without being mixed with or impaired by extraneous noises resulting from the operation of the mechanical parts.

My attachment can evidently be adapted and applied to various sizes and styles of phonographs without in any way disturbing the original construction of their parts, and when once attached it needs no further attention. If preferred, however, its essential features can be readily embodied in phonographs at the time when they are made. The term "soft rubber", as used herein, is intended to include rubber substitutes and other substances having substantially the same physical qualities as soft india rubber.

I claim:

1. The combination with a phonograph of a soft-rubber sheet interposed between

the motor and the support for the latter and provided with a soft-rubber rib surrounding the motor.

2. The combination with a phonograph of a soft-rubber sheet interposed between the motor and the support for the latter and provided with a soft-rubber rib surrounding the motor, and a cover surrounding said rib and overlying its outer face, out of contact therewith.

3. An attachment for phonographs comprising a sheet of soft rubber adapted to be interposed between the motor and the support for the latter and provided on one face with a soft-rubber rib adapted to surround the motor.

4. An attachment for phonographs comprising a sheet of soft rubber provided on one face with a soft-rubber rib adapted to surround the phonograph motor and located at a short distance from the outer edge of the sheet, and a cover provided with a flange adapted to rest upon the margin of said sheet and extending thence around and over the outer face of said rib, out of contact with the latter.

Signed at Boston, Mass., this 27th day of November, 1917.

ALEXIS W. PEVARE.
